J. J. KENYON

WASHING MACHINE

Filed Dec. 8, 1922

Inventor,
J. J. Kenyon.
By Fethertonough & Co.
Agents.

UNITED STATES PATENT OFFICE.

JOHN JEFFERSON KENYON, OF DETROIT, MICHIGAN.

WASHING MACHINE.

Application filed December 8, 1922. Serial No. 605,657.

To all whom it may concern:

Be it known that I, JOHN JEFFERSON KENYON, a subject of the King of Great Britain, and a resident of the city of Detroit, in the county of Wayne, in the State of Michigan, in the United States of America, have invented certain new and useful Improvements in Washing Machines, of which the following is the specification.

10 My invention relates to improvements in washing machines and the object of the invention is to devise a washing machine tub having a removable openwork false bottom that will support the clothes away from the bottom of the tub and which can be drawn up to raise the clothes out of the water therein.

15 A further object is to devise detachable means for pulling up the false bottom and a still further object is to devise means for holding the false bottom in any desired raised position.

20 My invention consists of a false bottom constructed and arranged all as hereinafter more particularly described and illustrated in the accompanying drawing in which:

25 Fig. 1 represents a vertical section, through a tub, of a washing machine showing my false bottom in position therein and showing the detachable means for raising up the same.

Fig. 2 is an enlarged sectional view through the line 2-2 Figure 1, and

30 Fig. 3 is an enlarged detail of one of the means for raising the false bottom up and supporting it in the desired position in the tub.

Figure 4 is an enlarged vertical section through the rims of the false bottom.

35 40 Like characters of reference indicate corresponding parts in the different views.

45 1 is the tub which in the present instance is provided with the removable vacuum cups 2 of the usual construction, supported on the reciprocable spindle 3 which operates in the sleeve 4 which extends through the bottom of the tub. 5 is the peripheral rim of the frame of the false bottom connected to the central boss 6 by means of the radially 50 extending webs 7, which are provided with a plurality of perforations 8. 9 is the open-

work top of the false bottom preferably constructed of wire mesh and having the outer edge turned down against the peripheral rim 5, an outer rim 10 being applied thereover and secured to the rim 5 by the bolts 18, thus effectively holding the wire mesh in place.

55 The hollow boss 6 is sufficiently large to permit the false bottom to be drawn up over the sleeve 4.

To the outer surface of the rim 10 is secured the upwardly extending triangular shaped bracket members 12 provided with the inwardly turned lugs 13 at their upper ends adapted to receive the eye swivels 14 at their lower ends.

60 65 15 are detachable hook members adapted to be hooked into the eyes of the swivels 14 at their lower ends and provided at their upper ends with the handles 16 and intermediate of their length with a plurality of downwardly turned hooks 17.

70 75 80 When the false bottom of the tub is in position it will be seen that the clothes during the actuating of the vacuum cups will be held away from the bottom of the tub thereby, thus aiding considerably in the effective washing of the clothes. When it is desired to remove the clothes from the washer, the vacuum cups 2 are first removed and then by hooking the hook members 15 into the eyes of the swivels 14, the user may pull up the false bottom the desired extent by pulling on the handles 16. Depending upon the height required the hooks 17 can be hooked over the edge of the lip of the tub 1 and thus retain the false bottom in the desired position. Consequently there will be no necessity of the user of the tub putting her hands into the hot water as is the case at present.

85 90 95 When the false bottom is at the bottom of the tub in the position illustrated in Figure 1, the hook members 15 can be removed from the eyes of the swivels 14.

What I claim as my invention is:

1. In a washing machine, the combination with a tub, of a false bottom comprising an inner peripheral rim, a central hollow boss and radial arms extending from the hollow boss to the inner rim, an open work top for

the false bottom having the outer edge turned down over the inner rim, and an outer rim applied over the inner rim and secured thereto for holding the edge of the open work top in position.

2. In a washing machine, the combination with a tub, of a vertically movable false bot-

tom inserted thereinto, hooked handle members detachably and rotatably secured to the false bottom and downwardly directed hooks positioned on the handle members at different heights and in diverging planes. 10

JOHN JEFFERSON KENYON.
